To all whom it may concern:

Be it known that I, George W. Rettie, a citizen of the United States, residing at city of Miami, in the county of Dade and State of Florida, have invented a new, original, and ornamental Design for Mobile Carousel, of which the following is a specification, reference being had to the accompanying drawings, forming a part hereof.

Figure 1 is a side elevational view of a mobile carousel showing my new design;

Figure 2 is a front elevational view thereof;

Figure 3 is a rear elevational view thereof;

Figure 4 is a top plan view thereof; and

Figure 5 is a top plan view thereof, partly in section with the canopy and part of supports removed, taken on line 5—5 in Figure 1.

The dominant features of my new design are shown in solid lines in the drawing.

I claim:

The ornamental design for a mobile carousel, substantially as shown and described.
